UNITED STATES PATENT OFFICE.

WILLIAM H. LOHMANN, OF WILMINGTON, DELAWARE, ASSIGNOR TO GENERAL CHEMICAL COMPANY, OF NEW YORK, N. Y., A CORPORATION OF NEW YORK.

CARBOY PACKAGE.

Application filed September 3, 1924. Serial No. 735,537.

My invention relates to carboy packages for containing and protecting carboys during transportation, and more particularly to that type of such packages in which the carboy is utilized for transporting acids and the like. Packages of this description are intentionally subjected to tests of various kinds in order to determine the degree of safety thereof with respect to the breakability of the carboys and in actual commercial use are subject to shocks incidental to the transportation and storage of carboy packages which develop impact forces tending to injure the carboys. The latter, as furnished for use in such packages, are oftentimes roughly made and of irregular surface conformation, this being particularly true with respect to the bottoms of such carboys. The result is that when such carboys are fitted into containers of existing types the bottoms thereof have a bearing on perhaps only a few points spaced apart and are otherwise at a distance from, and unsupported by, the supporting means. In such cases when the packages are subjected to the above mentioned tests, or to accidental or deliberate shocks resulting from handling or during transportation, great strain is placed upon the glassware by reason of the concentration of the forces developed as a result of such tests or shocks on but few points of the bottoms of the carboys with the result that the latter oftentimes break.

The particular object of the present invention is to overcome these objections and disadvantages by providing a novel and improved package in which the container is provided with a self-aligning bottom support on which the carboy is adapted to rest. A further object of the invention is to construct this bottom support in such a manner that it automatically adjusts itself to conform to the shape of the bottoms of the carboys, no matter how irregular they may be.

The invention contemplates further the construction of the bottom support which is resilient and adapted, by yielding, to absorb and neutralize shocks incidental to the above mentioned tests or to accidents or deliberate mishandling while the package is in commercial use. A still further object of the invention is to provide an improved means for cushioning the carboy against

lateral movements in the container. Other more specific objects will appear from the description hereinafter given and the features of novelty will be pointed out in the claims.

In the accompanying drawings, which show an example of the invention without defining its limits, Fig. 1 is a horizontal section of the improved carboy package; Fig. 2 is a vertical section on the line 2—2 of Fig. 1; Fig. 3 is a corresponding section on the line 3—3 of Fig. 1; and Fig. 4 is a vertical section on the line 4—4 of Fig. 1.

The carboy package comprises the customary container 5, which may be constructed in any conventional form and of suitable material, and which includes means whereby lateral movement of the carboy is prevented. The latter means may be of any conventional type and may consist of any kind of device customarily used for this purpose, although in the preferred construction the novel cushioning means illustrated by way of example in the drawings is desirable. This cushioning means may consist of main side members or strips 6 extending lengthwise of the container and supported therein so as to be capable of yielding laterally relatively to said container; for this purpose said main side members 6 may be mounted upon blocks 7 located in spaced relation at the intermediate portions of said members 6. The latter thus project in opposite directions beyond said blocks and at their opposite end portions are unsupported and spaced from those parts of the container upon which said blocks 7 are fixed; as a result of this the opposite end portions of said members 6 are inherently elastic or yielding. The members 6 may be located at convenient points within the receptacle 5, it being understood that the blocks 7 are correspondingly attached to support said members 6 in the desired manner; in the illustrated example the latter are positioned in the four corners of the rectangular receptacle 5 and the blocks 7 are accordingly secured to triangular strips 8 fitted into said corners and secured in place in any conventional manner as shown in Fig. 1. Auxiliary cushioning devices in the form of auxiliary side members 6^a extend lengthwise of, and in engagement with, the carboy *a* and are carried by the main side members 6 so as to be capable of yielding laterally relatively thereto.

In the illustrated example the auxiliary side members 6^a are mounted in cooperating pairs upon the projecting end sections of the main side members 6 by means of blocks 7^a; the latter are located at intermediate points of the auxiliary side members 6^a which project in opposite directions beyond said blocks 7^a and consequently are themselves capable of yielding under pressures, or other forces, exerted upon such projecting portions. As will be apparent from Fig. 4 of the drawings, the main side members 6 and the auxiliary side members 6^a in cooperation with each other, comprise cushioning means adapted to yieldingly prevent shifting of the carboy *a* in the receptacle 5 in directions transverse thereto. The carboy *a* rests upon a bottom support which, in addition to functioning as a resilient support arranged to yield under impact forces developed in said carboy from any cause and thereby protect the same against injury and breakage, is constructed as a self-aligning bottom support adapted to automatically adjust itself to conform to the bottom shape of said carboy. In its illustrated form, the yielding and self-aligning bottom support comprises a main member 9 located upon the bottom 10 of the receptacle 5 and constructed so as to be capable of a rocking movement thereon in a vertical plane; for this purpose the lower surface of the main member 9 may taper toward its opposite ends, as indicated at 11. With this arrangement the member 9 is supported at an intermediate point and has its opposite end portions free and unsupported as shown in Figs. 2 and 4; the opposite end portions of said member 9 are consequently capable of yielding toward the bottom 10 and accordingly possess an inherent resiliency. The support comprises a further auxiliary means extending transversely to the main member 9 and capable of rocking thereon in a plane transverse to the plane of movement of said main member 9. The auxiliary supporting means in the illustrated example consists of two auxiliary members 12 located in spaced parallel relation to each other and mounted upon the member 9 in transverse relation thereto, as shown in Fig. 1; the auxiliary members 12 are supported upon the opposite free end portions of the member 9 and partake of the yielding movements thereof.

To provide for the independent rocking movements of the auxiliary members 12, the upper surface of the member 9 may be inclined transversely in opposite directions, as indicated at 13 in Fig. 3. As shown in Figs. 1 and 3 the auxiliary members 12 project beyond the member 9 in opposite directions and at their opposite ends, which may be inclined, as indicated, for instance, in Fig. 1, are inherently resilient and yielding.

In order to maintain the support as a unit in its position upon the bottom 10 of the receptacle suitable fastening devices 14 may be provided while additional fastening devices 15 may serve to fix the auxiliary members 12 in position upon the main member 9. It will be understood that the fastening devices 14 and 15 are always of such character as not to interfere with the intended rocking and yielding movements of the members 9 and 12, and further that while these fastening devices are shown in the form of nails, this is intended only as an example. Obviously, any other suitable devices whereby the support as a whole and the auxiliary members 12 may be fixed in their intended positions without interference with the proposed movements thereof, may be substituted if desired.

In the preferred construction, the member 9 comprises a single section of elastic wood while the auxiliary members 12 are constructed of sections of softer wood and preferably have their upper surfaces corrugated lengthwise as indicated at 16; the auxiliary members 12 may thus be termed cushions upon which the carboy 7 is adapted to rest.

In practice, the carboy *a* is placed within the receptacle 5 and is caused to rest upon the members 12, as shown in Fig. 2; by its weight the carboy *a* will cause the members 12 and the member 9 or, in other words, the bottom support as a whole, to automatically adjust itself in a manner to conform to the bottom shape of the carboy 7, whatever this may be. That is to say the main member 9 will adjust itself to bring the auxiliary members 12 into the most efficient supporting positions, and the members 12 will independently adjust themselves to meet the surface conformation of the bottom of the particular carboy *a*. As previously stated, the character of the fastening devices 14 and 15 is such as not to interfere with this automatic adjustment of the parts. With the improved construction, the carboy *a* is uniformly and evenly supported throughout its entire bottom, this result being automatically obtained without requiring any special manual manipulation to adjust the bottom support. This fact, coupled with the inherent resiliency of the bottom support, will cause any impact forces which may be developed from any cause in the carboy, to be absorbed and neutralized without injury to the latter.

It will be noted that the member 9 is supported upon a central point and otherwise is out of contact with the bottom 10 of the receptacle, and that the auxiliary members 12 are supported at single points upon the member 9 and project beyond the same in opposite directions out of contact thereof. In other words the member 9 and the auxiliary members 12 together constitute a bot-

tom support capable of compound rocking movements relatively to the bottom 10 in vertical planes transverse to each other and which possesses inherent resiliency independent of such rocking movements. With the arrangement, not only the inherent elasticity of the material of which the bottom support is constructed is utilized to absorb shocks, but the ability of the members 5 of said support to yield relatively to the bottom of the container and to each other increases this shock absorbing ability of the bottom support. The aforesaid construction and arrangement of the members of the bottom support also permit the same to readily adjust themselves to any unevenness and any inequalities which may exist in the bottom of the carboy.

To still further increase the resiliency of 10 the bottom support and to still further reduce the possibility of injury to, or breakage of the carboy *a* as a result of impact shocks, the bottom 10 of the receptacle 5 may be constructed to yield under the effect of 15 forces developed in said carboy *a*. For this purpose cleats 10^a, or their equivalent, may be provided exteriorly upon the lower part of the receptacle, or the latter may be constructed in any other suitable manner to 20 space the intermediate portions of the bottom 10 from the surface upon which the carboy package is resting. With this arrangement the inherent elasticity of the bottom 10 is added to the resiliency inherent in the afore- 25 said bottom support to neutralize and absorb any shocks which otherwise would tend to injure or break the carboy *a*. The cushioning properties which are inherent in the auxiliary members 12, particularly when the 30 latter are constructed of soft wood, added to the resiliency of the main supporting member 9 resulting both from its physical characteristics and the method of mounting said member 9, plus the resiliency which is 35 present in the bottom 10 because of its arrangement and inherent properties of the wood from which it is made, serve to develop a multiplied yieldability and a very high 40 degree of neutralization and absorption of 45 shocks.

While the means for supporting the carboy 10 is capable of developing a most effective cushioning of the carboy against 50 shocks, it at the same time provides a firm 55 and efficient support therefor in the container, the arrangement as a whole providing a carboy package which is of maximum serviceability and utility.

The improved and novel cushioning means 60 and bottom support may be incorporated in existing carboy packages without material trouble or cost and provides an efficient means whereby the danger of breakage or of injury to the carboy itself is reduced to 65 a minimum.

Various changes in the specific form shown and described may be made within the scope of the claims without departing from the spirit of the invention.

I claim:

1. In a carboy package, the combination of a receptacle adapted to contain a carboy, means whereby said carboy is held against lateral movement in said receptacle, and a bottom support set upon the bottom of said receptacle for supporting said carboy therein, said bottom support being capable of compound rocking movements relatively to said bottom, in vertical planes transverse to each other, for automatically adjusting itself to conform to the bottom shape of said carboy.

2. In a carboy package, the combination of a receptacle adapted to contain a carboy, means whereby said carboy is held against lateral movement in said receptacle, and a bottom support set upon the bottom of said receptacle for supporting said carboy therein, said bottom support comprising a main section capable of rocking movements upon said bottom, and auxiliary means carried by said main section and capable of independent rocking movements thereon, the rocking movements of said main section and auxiliary means being in vertical planes transverse to each other to automatically adjust said bottom support in conformity with the bottom shape of the carboy.

3. In a carboy package, the combination of a receptacle adapted to contain a carboy, means whereby said carboy is held against lateral movement in said receptacle, a main support mounted upon the bottom of said receptacle and capable of movement relatively thereto, and auxiliary supporting means carried by said main support for engagement with the bottom of the carboy, said auxiliary means being bodily movable by said main support to meet the bottom shape of said carboy and being independently movable relatively to said main support in conformity with said bottom shape of said carboy.

4. In a carboy package, the combination of a receptacle adapted to contain a carboy, means whereby said carboy is held against lateral movement in said receptacle, a main supporting member mounted upon the bottom of said receptacle and capable of rocking relatively thereto, said main member having an inherent resiliency independent of its rocking movements, and auxiliary supporting means extending transversely to said supporting member for engagement with the bottom of the carboy and capable of rocking on said main member in a plane transverse to the plane of movement thereof, said auxiliary means having an inherent resiliency independent of its rocking movements, said member and means constituting a support

- 4
- for said carboy arranged to automatically adjust its position to conform to the bottom shape thereof and to yieldingly support said carboy upon the bottom of said receptacle.
5. In a carboy package, the combination of a receptacle adapted to contain a carboy, means whereby said carboy is held against lateral movement in said receptacle, a main supporting member mounted upon the bottom of said receptacle and capable of rocking relatively thereto in a vertical plane, said main member having an inherent resiliency independent of its rocking movements, and a pair of spaced auxiliary members mounted upon said main member and extending transversely thereto for engagement with the bottom of a carboy, said auxiliary members being capable of independently rocking on said main member in vertical planes transverse to the plane of the movement of said main member, and each having an inherent resiliency independent of its rocking movements, said auxiliary members and said main member together constituting a support for said carboy adapted to automatically adjust its position to conform to the bottom shape thereof and to yieldingly support said carboy upon the bottom of said receptacle.
6. In a carboy package, the combination of a receptacle adapted to contain a carboy, means whereby said carboy is held against lateral movement in said receptacle, a main supporting member mounted upon the bottom of said receptacle and tapering toward its opposite ends so as to be capable of rocking on said bottom and to develop an inherent resiliency in its opposite end portions independent of its rocking movements, and auxiliary supporting members mounted upon said main member for engagement with the bottom of a carboy and capable of rocking relatively to said main member in conformity with the bottom shape of the carboy.
7. In a carboy package, the combination of a receptacle adapted to contain a carboy, means whereby said carboy is held against lateral movement in said receptacle, a main supporting member mounted upon the bottom of said receptacle and tapering toward its opposite ends along its lower surface so as to be capable of rocking on said bottom and to develop an inherent resiliency in its opposite end portions independent of its rocking movements, the upper surface of said main member being inclined transversely in opposite directions, and auxiliary supporting members mounted upon said member for engagement with the bottom of a carboy and arranged to rock upon the upper surface thereof to automatically conform themselves to the shape of said carboy bottom.
8. In a carboy package, the combination of a receptacle adapted to contain a carboy, means whereby said carboy is held against lateral movement in said receptacle, a main section of elastic wood mounted upon the bottom of said receptacle and capable of rocking movements thereon and two sections of softer wood mounted upon said main section for engagement with the bottom of a carboy and capable of rocking movements relatively to said main section in conformity with the shape of said carboy bottom, said sections of wood together constituting a support for the carboy adapted to automatically adjust itself to conform to the bottom shape thereof and having a resiliency independent of its rocking movements to cause said support to yield under impact forces developed in said carboy.
9. In a carboy package, the combination of a receptacle adapted to contain a carboy, means whereby said carboy is held against lateral movement in said receptacle, a main supporting member movably mounted upon the bottom of said receptacle for automatically adjusting its position thereon in accordance with the shape of the bottom of said carboy and possessing an inherent resiliency independent of its movements of adjustment and a plurality of auxiliary members mounted in spaced relation upon said main member for engagement with the bottom of said carboy, said auxiliary members being independently movable relative to said main member in conformity with the shape of said carboy bottom and having an inherent resiliency independent of the movements of adjustment whereby said carboy is yieldingly mounted upon the bottom of said receptacle.
10. In a carboy package, the combination of a receptacle adapted to contain a carboy, a yielding bottom forming part of said receptacle, means whereby said carboy is held against lateral movement in said receptacle and a yielding support for said carboy set upon the yielding bottom of said receptacle and adapted to yield therewith and to independently yield under impact forces developed in said carboy.
11. In a carboy package, the combination of a receptacle adapted to contain a carboy, a yielding bottom forming part of said receptacle, means whereby said carboy is held against lateral movement in said receptacle, a main supporting member set upon said yielding bottom and capable of yielding relatively thereto and auxiliary supporting members carried entirely by said main member for engagement with the bottom of a carboy and capable of yielding relatively to said main member, said yielding bottom and yielding members together forming a bottom support for said carboy the elements of

which are adapted to yield as a unit and independently of each other under impact forces developed in said carboy.

12. In a carboy package, the combination of a receptacle adapted to contain a carboy, a yielding bottom support in said receptacle arranged to support said carboy therein, main side members extending vertically in said receptacle, supporting means located at intermediate portions of said main members for mounting the latter upon and in spaced relation to the upright walls of said receptacle, the opposite free end portions of said main members being free and possessing an inherent resiliency, auxiliary members, supporting means located at intermediate portions of said auxiliary members for mounting the latter upon the resilient free end portions of said main side members in spaced relation thereto, the ends of said auxiliary members being free and disconnected and capable of yielding relatively to said receptacle and to said main members, said auxiliary members being adapted to engage said carboy to yieldingly prevent lateral movement thereof in said container.

13. In a carboy package, the combination of a receptacle adapted to contain a carboy, a yielding bottom support in said receptacle for said carboy, main side members extending vertically in said receptacle and yieldingly mounted upon the side walls thereof,

and auxiliary side members mounted in spaced relation in cooperating pairs upon each of said main side members so as to be capable of yielding relatively thereto, said auxiliary side members extending lengthwise of and engaging the carboy at spaced points in the direction of its major axis to yieldingly prevent lateral movement of said carboy in said container.

14. In a carboy package, the combination of a receptacle adapted to contain a carboy, a yielding bottom forming part of said receptacle, a main supporting member mounted on said yielding bottom and capable of yielding relatively thereto, auxiliary supporting members carried by said main supporting member and capable of yielding relatively thereto, said yielding bottom and yielding members together forming a bottom support for said carboy adapted to yield under impact forces developed therein, main side members extending lengthwise of said receptacle and yieldingly mounted therein, and auxiliary side members mounted in cooperating pairs upon said main side members, said auxiliary side members extending lengthwise of and engaging the carboy to yieldingly prevent lateral movement thereof in said container.

In testimony whereof I have hereunto set my hand.

WILLIAM H. LOHMAN.
